(57) **CLAIM**

I claim the ornamental design for a window for a door, as shown and described.

DESCRIPTION

FIG. 1 is a perspective view of the window for a door;
FIG. 2 is a top view thereof;
FIG. 3 is a front view thereof, the rear view being identical;
FIG. 4 is a side view thereof, the opposite side view being identical; and,
FIG. 5 is a bottom view thereof.
The window is shown broken apart to indicate that no specific thickness is claimed.
